US00D848973S

(12) **United States Design Patent** (10) **Patent No.:** **US D848,973 S**
(45) **Date of Patent:** **** May 21, 2019**

(54) **HEADSET**

- (71) Applicant: **Performance Designed Products LLC**,
Burbank, CA (US)
- (72) Inventor: **Ozhan Karacal**, San Diego, CA (US)
- (73) Assignee: **Performance Designed Products LLC**,
Burbank, CA (US)

(**) Term: **15 Years**

(21) Appl. No.: **29/612,925**

(22) Filed: **Aug. 4, 2017**

(51) LOC (11) Cl. **14-01**

(52) U.S. Cl.

USPC **D14/205**

(58) **Field of Classification Search**

USPC D14/205, 206, 188, 192, 225, 226, 372;

Primary Examiner — Paula Allen Greene

(74) Attorney, Agent, or Firm — Knobbe, Martens, Olson & Bear LLP

(57) **CLAIM**

The ornamental design for a headset, as shown and described.

DESCRIPTION

FIG. 1 is a top perspective view of a headset embodying my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict environment that forms no part of the claimed design.
